Attorney.

UNITED STATES PATENT OFFICE.

JOHN H. COMER, OF LIBERTY HILL, TEXAS.

ENSILAGE-PACKER FOR SILOS.

1,334,521.

Specification of Letters Patent. Patented Mar. 23, 1920.

Application filed May 6, 1919. Serial No. 295,199.

To all whom it may concern:

Be it known that I, JOHN H. COMER, a citizen of the United States, residing at Liberty Hill, in the county of Williamson 5 and State of Texas, have invented certain new and useful Improvements in Ensilage-Packers for Silos, of which the following is a specification.

This invention relates to packing devices 10 adapted for packing ensilage in cylindrical silos as the ensilage is delivered thereinto.

An object of the invention is to provide a novel and efficient device of this general character by means of which the center and 15 edges of the ensilage will be packed with equal firmness and solidity.

The invention consists in the details of construction and in the combination and arrangement of the several parts of my improved device whereby certain important advantages are attained and the device rendered simpler, less expensive and otherwise more convenient and advantageous for use 20 as will be best understood from a consideration of the following detailed description, taken in connection with the accompanying drawings forming a part of this specification.

In the drawings Figure 1 is a vertical elevation of a silo, a part being broken away showing my improved packing device in elevation therein. Fig. 2 is a horizontal sectional view taken on the line X—X of Fig. 1. Fig. 3 is an enlarged transverse 35 sectional view of a spider that carries the axles upon which the packing rollers are mounted. Fig. 4 is a plan view of the same.

As disclosed in the drawings 1 denotes a type of cylindrical silo of wood or other 40 suitable material with the operation of which my novel method of packing ensilage is intended to be practised. Disposed vertically and centrally within the silo is a shaft 2 which is angular in cross section and preferably of square metal tubing of convenient 45 lengths for handling, and may be coupled together in any suitable manner; the uppermost section of the tube being slidably disposed through, and rotated by a bevel gear 3. A rectangular frame work is disposed on the upper edge of the silo, the sills 4 thereof being secured thereto and provided with suitable supports for the gear 3. In 50 brackets 5 carried by the said frame, there

is supported a horizontal shaft 6, the inner 55 end of which carries a bevel pinion 7 meshing with the gear 3, while the other end of the shaft carries a pulley 8 shown connected through belt 9 to a gas engine 10, or it may be driven by any other convenient source of 60 power.

Carried by the lowermost section of the shaft 2 is a spider 11 to which is pivoted at 12, the inner ends of radial axles 13, while the other ends extend to a point adjacent 65 the inner face of the silo. On the outwardly extended end of each axle 13 there is mounted a roller 14, and on the axles, between the inner end of the rollers and the collars 15, are coil springs 16 that normally 70 urge the rollers outwardly on the axles. These rollers are arranged to pack the ensilage near the outer edge of the silo. On each of the axles 13 are revolvably mounted two other rollers 17 and 18 which turn in a 75 circular path, the latter close to the spider 11, so as to pack the ensilage near or at the center of the silo.

Carried by the shaft 2, at a suitable distance above the rollers 14 is a frame comprising radial arms 19, each arm is formed of two equal parts that radiate from the sides of the shaft, with the ends adjacent thereto joined respectively by straps 20 and 21, adapting them for vertical slidable 80 movement upon the shaft 2. Secured to the shaft 2 at a suitable distance above the arms 19, but not in alignment therewith, are arranged similar radial arms 22, to the respective outer ends of which are secured braces 85 23 that decline downwardly and are secured to the ends of arms 19, thence vertically 90 downward to the axles 13, through the apertured ends of which the axles pass, the arms 22 being rigidly supported by braces 24. 95 It will be noted that the outer end of the rollers are rounded, whereby any binding between them and the side wall of the silo is prevented. The rollers are also shown with the rim or face cut away at regular 100 intervals, but they may be solid if preferred, and also ribbed if desired. Carried by one of the arms 22 is a spreader 25, secured thereto by vertical supports 26 and adapted to evenly spread and distribute the 105 ensilage for the convenient passage of the rollers, and one or more may be employed. Boxlike receptacles 27 are provided on the

arms 19 in which weights may be placed when desired to increase the pressure of the rollers on the ensilage.

From the foregoing description, it is thought to be obvious that an ensilage packer constructed in accordance with my invention is particularly well adapted for use by reason of the convenience and facility with which it may be assembled and operated, and it will also be obvious that my invention is susceptible of some changes and modifications without departing from the principles and spirit thereof, and for this reason I do not wish to be understood as limiting myself to the precise arrangement and formation of the several parts herein shown in carrying out my invention in practice.

Having thus described my invention, what I esteem as new and desire to secure by Letters Patent of the United States, is—

1. An ensilage packing device for a silo including a vertical rotatable sectional shaft suitably supported within the silo, means

for driving the shaft, a spider carried by the lowermost section of said shaft, radially disposed transverse axles pivotally connected at one end to the spider while the other end extends to a point adjacent the side of the silo, rollers mounted on the axles and the outer roller on each axle being yieldingly spring pressed outwardly by coil springs mounted on the shafts.

2. An ensilage packing device for a silo including a vertical rotatable shaft, packing elements on radially disposed axles mounted on a spider carried by the lower end of the shaft, radially disposed transverse arms slidably disposed on the shaft above the packing elements, similarly disposed arms rigidly secured to the shaft above the slideable arms, and braces extending from their ends to, and connected with the ends of the slideable arms and to the axles, as herein described.

In testimony whereof I affix my signature.

JOHN H. COMER.
